(57) **CLAIM**

The ornamental design for an integrated signature pad and fingerprint reader, as shown and described.

DESCRIPTION

FIG. 1 is a perspective view of the integrated signature pad and fingerprint reader;

FIG. 2 is a front view of the integrated signature pad and fingerprint reader illustrated in FIG. 1;

FIG. 3 is a plan view of the integrated signature pad and fingerprint reader illustrated in FIG. 1;

FIG. 4 is a back view of the integrated signature pad and fingerprint reader illustrated in FIG. 1;

FIG. 5 is a first side view of the integrated signature pad and fingerprint reader illustrated in FIG. 1;

FIG. 6 is a second side view of the integrated signature pad and fingerprint reader illustrated in FIG. 1; and,

FIG. 7 is a bottom view of the integrated signature pad and fingerprint reader illustrated in FIG. 1.
